UNITED STATES PATENT OFFICE.

PAUL R. GOLDEY, OF PHILADELPHIA, PENNSYLVANIA, ASSIGNOR, BY MESNE ASSIGNMENTS, TO THE GENERAL EQUIPMENT COMPANY, OF NEW JERSEY.

AUTOMATIC MAGNETIC CIRCUIT-BREAKER.

SPECIFICATION forming part of Letters Patent No. 627,997, dated July 4, 1899.

Application filed October 26, 1898. Serial No. 694,582. (No model.)

To all whom it may concern:

Be it known that I, PAUL R. GOLDEY, a citizen of the United States, residing in the city and county of Philadelphia, State of Pennsylvania, have invented a new and useful Improvement in Automatic Magnetic Circuit-Breakers, which improvement is fully set forth in the following specification and accompanying drawings.

10 My invention relates to circuit-breakers of the type in which the breaker is actuated to open suitable contact devices by an abnormally-excessive flow of current through the line or when the current falls below a predetermined amount, said breaker being also actuated by the flow of current through circuits other than the circuit opened by the circuit-breaker itself; and the object of the invention is more particularly for increasing the 20 efficiency of devices of this character over similar machines now in use, whereby the danger of causing an arc between the ends of the circuit-wire or contact devices opened by the breaker will be reduced.

25 It further consists in the provision of a counterbalanced or weighted lever, forming a hammer, which is movably supported above an unlocking-lever, said weight being held in the desired position by means of a suitable trigger of novel construction.

30 It further consists of novel details of construction, all as will be hereinafter fully set forth, and particularly pointed out in the claims.

35 Figure 1 represents a side elevation of an automatic magnetic circuit-breaker embodying my invention. Fig. 2 represents on an enlarged scale a vertical sectional view of a portion of the apparatus seen in Fig. 1, showing in dotted lines the different positions the parts assume due to the actuation of the electromagnet of the circuit-breaker.

Similar letters of reference indicate corresponding parts in the figures.

40 Referring to the drawings, A designates a circuit-breaker, the same being supported upon a suitable wall or switchboard and consisting of a bracket B, having the arms C and D projecting therefrom.

45 E designates a switch-carrying arm which

is pivoted to the arm D at the point F, said switch-carrying arm having an offset upper portion G, in which is located the solenoid-coil or electromagnet H, of copper or other material, which is in electrical connection with the circuit intended to actuate the electromagnet and has the conductor J leading therefrom to a member of the contact device K, the latter consisting of thin plates of the usual construction.

55 L designates the core of the magnet H, in which is located the armature M, which latter has attached thereto the yoke N, of iron or other material.

60 P designates a lock-nut, of brass or other material, which has the adjustable screw-bolt Q passing therethrough, the head R of which is adapted to contact with the extremity S of the lever T, said portion S being normally in such a position that the lower surface of the 65 head R rests thereon, with a clearance or free space between the lower portion of the lever T and the adjacent face of the yoke N, thus permitting a free and unimpeded movement of the yoke N. The lever T is fulcrumed on 70 the pin U, which latter is engaged by the recess or nose V of the locking-lever W, which is mounted on the shaft X, the latter having 75 its bearings in the arms C.

80 Y designates an extremity of the lever T, which is adapted to engage the recess Z of the trigger A', which latter is pivoted at B' to the lever C', which carries the weight or counterbalance D', said arm being freely movable on the shaft X, and it being noted that said 85 weight D' is located at one side of the shaft X, said arm and weight forming a hammer, and it being seen that said trigger has the lug E' thereon, which is held normally between the stationary pin F' and the extremity Y of 90 the lever T, said trigger being held in its proper position by means of said spring G'.

95 H' designates a link having one end pivoted at J' to the exterior K' of the switch-carrying arm E, while the other end of said link is pivoted to the arm L', which is mounted on the shaft X.

M' designates a roller mounted on the rod N', which is cushioned on the spring P'.

100 W^X designates a coil or other spring having

one end attached to the lever W and its other end secured to a suitable fixed point, as the bracket C, whereby the lever W is always normally held in the position seen in full lines 5 in Fig. 2.

The operation is as follows: The parts in their normal position appear as seen in Fig. 1, and if the current falls below a predetermined amount or upon any increase of the 10 current above the normal, or on any variation of the flow of current through other circuits than the circuit opened by the circuit-breaker itself, the proper connections having been made, the armature M will be drawn 15 upwardly by the action of the magnet H, thereby raising the yoke N and the end S of the lever T, it being noted that a free initial movement of said yoke takes place before the latter strikes the end S of the lever T. By the 20 above action the trigger A' will be depressed to the left of the portion seen in full lines in Fig. 2, whereupon the hammer or weight D', being unsupported, falls and contacts with the locking-lever W, thereby lifting the 25 positive end thereof out of engagement with the pin U, whereupon the switch-carrying arm E, being detached and the spring P' pressing on the extension K' through the medium of the rod N' and roller M' swings to the right 30 of the position seen in the figures in the direction of the arrow a, (seen in Fig. 2,) and the contact is then broken between the plates constituting the contact device K, as is evident.

I desire to call especial attention to the function 35 of the trigger A' and its adjuncts and also to the location of the weight or hammer D, since its operation is rendered much more effective and instantaneous than in other constructions where said hammer and trigger are 40 dispensed with.

It will be apparent that in order to reset the circuit-breaker it is only necessary that the parts be moved from the position seen in dotted lines in Fig. 2 to the position seen in full 45 lines again, in which latter position the circuit-breaker is again ready to be operated, it being of course understood that the arm E is moved from the position in which it falls in the direction of the arrow a to the left until 50 the parts assume the position seen in full lines, the trigger A' being locked in operative position again between the end Y of the lever T and the pin F', while the recess V of the lever W is caused to engage the pin U again, 55 and thus serves to hold the parts in position in readiness to be operated again.

Having thus described my invention, what I claim as new, and desire to secure by Letters Patent, is—

60 1. In a circuit-breaker, the combination of a hammer, a trigger carried thereby, a locking-lever, means for locking said trigger in position, and devices for operating the locking means and said trigger when the current 65 actuates the electromagnet.

2. In a circuit-breaker, a hammer suitably supported and standing normally at one side

of its fulcrum, a trigger pivoted to said hammer, a spring common to said hammer and to said trigger, whereby the latter is held in normal position, a switch-carrying arm, a solenoid or magnet supported thereby, a locking-lever for said arm, and a lever operated by the armature of said magnet, said lever engaging said trigger. 70

3. In a circuit-breaker, a pivoted switch-carrying arm, a solenoid and armature carried thereby, a yoke attached to said armature and operated by said solenoid, a lever suitably fulcrumed and operated by said yoke, 80 a hammer suitably supported, a trigger attached to said hammer and having an end bearing on the end of said lever, a locking-lever for holding said switch-carrying arm in position, and devices operated by said hammer for effecting the breaking of the circuit when the current actuates the electromagnet. 85

4. In a circuit-breaker, a pivoted switch-carrying arm, a solenoid and armature carried thereby, a yoke attached to said armature and operated by said solenoid, a lever suitably fulcrumed and operated by said yoke, 90 a hammer, a fulcrum therefor, a trigger attached to said hammer and having a portion engaging said lever, said hammer standing normally at one side of its fulcrum, so that when said lever is disconnected said hammer falls, a locking-lever for holding said switch-carrying arm in position, and means for enabling said hammer to impact on said locking-lever when the current actuates the electromagnet. 95

5. In a circuit-breaker, a pivoted switch-carrying arm, a lever pivoted therein, a solenoid carried by said arm, connections common to the armature of said solenoid and to said lever for operating the latter when the current actuates the electromagnet, a hammer suitably supported, a trigger carried by said hammer and having a portion thereof held between a pin or abutment and the end of the lever operated by said solenoid, a spring for said trigger and a locking-lever adapted to be actuated by said hammer when the latter falls. 115

6. In a circuit-breaker, a pivoted switch-carrying arm E, an electromagnet and its armature supported by said arm, a lever T suitably fulcrumed, connections common to said armature and to said lever, whereby the latter is operated when the current actuates the electromagnet, a hammer D' supported upon its fulcrum and at one side thereof, a trigger A' carried by said hammer, a spring G' common to said hammer and to said trigger, the latter having a projection or lug E', which is held between the extremity Y of the lever T and the pin F', a locking-lever W suitably supported, a pin engaged by a recess in said locking-lever, the extremity of the latter being adapted to be depressed by the falling of said hammer thereon when the current actuates the electromagnet. 125

7. In a circuit-breaker, the combination of

a hammer suitably supported, a trigger carried by said hammer, a locking-lever suitably supported and adapted to be actuated by the impact of said hammer when said trigger is
5 disengaged and said hammer falls, said hammer normally standing at one side of its fulcrum, means for locking said trigger in posi-

tion and devices for operating the locking means and said trigger when the current actuates the electromagnet.
